UNITED STATES PATENT OFFICE.

GEORGE ALBERT MOORE, OF NEW YORK, N. Y., ASSIGNOR TO THE CARD PRINTER COMPANY, OF NEW YORK, N. Y., A CORPORATION OF NEW YORK.

COIN-OPERATED PRINTING-MACHINE.

No. 820,514.

Specification of Letters Patent.

Patented May 15, 1906.

Application filed June 18, 1904. Serial No. 213,073.

To all whom it may concern:

Be it known that I, GEORGE ALBERT MOORE, a citizen of the United States, and a resident of the city of New York, N. Y., have invented certain new and useful Improvements in Coin-Operated Printing-Machines, of which the following is a full, clear, and exact description.

The object of this invention is the construction of an inclosed machine containing printing characters, paper, inking devices, and printing mechanism, and having external character-setting means, which printing mechanism can only be put into operation for the printing and delivery of a designated number of prints by the introduction of a coin.

Referring to the drawings forming part of this specification, Figure 1 is a side elevation of the machine embodying my invention, the inclosing case and certain other part being shown in section and other portions being represented as broken away for the better illustration of the mechanism. Fig. 2 is a front elevation of the same with the lower half of the machine shown in section. Fig. 3 is a perspective view of a few of the rack-pulls by means of which the type-wheels are externally operated. Fig. 4 is a plan view of the entire machine and case.

The inclosing case of this machine is designated by the reference-numerals 1 2, 1 being the top and 2 the preferably transparent front, 3 being the delivery-shelf, upon which the completely-printed sheets or cards are delivered to the purchaser, and 4 being the coin-chute for the reception of the designated coins.

The type-disks 10 are preferably twenty in number and journaled side by side upon the fixed bar 11, terminally supported by the side frames 5, as shown in Fig. 2. Each type-disk contains a full set of alphabetic type characters upon its periphery, the same occupying less than one-half its circumference and being designated by the character 12 in Fig. 1. The other half of each type-disk is formed with spur-teeth 15, intermeshing with a rack-bar 16, longitudinally 50 movable beneath it, and said rack-bar is manipulated from the exterior of the machine-case by a rack-pull (shown in Figs. 1 and 3) comprising a shank 17 18 and a finger-piece 19, as hereinafter more fully described.

By pulling out said rack-pulls to various distances the type-disks are rotated to present the desired selection of type characters in a single line upon the topmost circumference of the disks, and hence in a position to meet the under surface of any card-paper which may be pressed down thereon. To retain these type-disks in their selected position, each thereof is formed with a series of small holes 13, equal in number to the type characters on its periphery, and through such holes 65 a slender rod 20 is designed to be inserted.

To ink the selected type, the ink-roll 40 is provided, the same being loosely carried by the light frame 41, pivoted at 42, eccentric to the bar 11, as shown in Fig. 1. This frame 70 is formed with an arm 43, from which rigidly projects a pin 44, from the extremity of which pin rises a connecting-rod 45 to the vertically-movable impression member of the machine. As the impression member 75 descends in the operation of printing the ink-roll is thereby swung forward and over the selected type, inking the same as it passes, and thence beyond to a position where it will not interfere with the further descent of the 80 impression member. When the latter rises, said roll is returned to its original starting-point.

It is of course necessary to provide the slot 48 in the side frame 5 for the passage of the 85 pin 44 from the frame member, which is located within such frame-plates or side frames to the connecting-rod 45, which is external to the same.

To select the various type characters for 90 printing any one name or other word or set of words,—as, for example, the name “George A. Moore”—the first type-disk is turned by pulling upon the rack-pull until the letter “G” is uppermost, then the second 95 disk is turned to present an “E,” then the third to present an “O,” and so on to the end of the name, after the placing of each disk the rod 20 being moved along to enter the hole 13 therein immediately beneath the type 100 character selected. Inasmuch as the front and sides of the machine-case are of glass, the type selected can be readily seen from the outside, a small strip of mirror 47 being provided for reversing the characters and so presenting them in a readable shape to those unaccustomed to printers’ type. Such mirror 105 can be carried by the light frame 41, and

thereby removed from contact with the impression member when the latter descends. On many accounts, however, it is preferable to locate a suitable array of alphabetical characters, as 102, exterior to the case, by means of which and a small pointer connected with each rack-pull the latter, and hence the type-disks, can be properly arranged.

- The means for operating the locking-rod 20 consists of the following: Said rod is slidably supported in the tube 22 and is formed with an enlargement 21, from which a pin 23 projects through a slot in said tube into a notch 25 at the upper end of the lever or arm 24. This arm is rigid with the toothed segment 26, pivoted at 27 to the support 28, and said segment meshes with a pinion 35, fixed on the end of the shaft 34, which extends through the front 2 to the exterior of the case. On the outer end of said shaft is the pointer 32 and manipulating handle or knob 33. The parts are so arranged that when this pointer is turned to any particular number on the dial 30 the extremity of the rod 20 will just penetrate a hole 13 in the type-disk 10, corresponding to such number—that is, if the pointer is turned to the number "7," as shown in Fig. 2, the rod end will just enter the seventh type-disk from the left-hand side. The type-disk is designated by the number above its slot 101.
- The impression member 50 is vertically slideable on the frame-rods 78 and is operated by means of the shaft 51, pitman 52, and crank-arm 53, any suitable means, as the crank-handle 59, being provided at the exterior of the machine-case for the rotation of such shaft by hand. To lock this shaft, and hence the printing mechanism, against operation except upon the introduction of the designated coin, said shaft is provided with the two disks 54 and 56, the former being made with ratchet-teeth throughout its periphery and the other having only one or two such teeth, but the teeth in the two disks being oppositely faced. The pawl 55, which engages the disk 54, rests thereon continuously by gravity, so that the shaft 51 can only be turned in one direction, while the locking-dog 57 is normally held either by gravity or a small spring (indicated in Fig. 1) from engagement with the disk 56. To hold this dog in engagement with said disk, there is provided the lever 60, rigid with the shaft 61, and with its horizontal section provided with the pin 63. When the upper arm of this bell-crank lever 60 is moved toward the notched disk 56, said pin is carried down into engagement with the notch 66 of the upper length of the locking-lever 65, pivoted at 68 to the coin-chute 4 and whose lower extremity 67 is bent toward said chute. When said pin is thus brought into the field of said notch, the lower section of the locking-lever swings 65 within the coin-chute by gravity and said

notch locks said pin, and hence the bell-crank lever, in the position described; but this position of the upper arm of said bell-crank lever holds the dog 57 in engagement with the notched disk 56 and so secures the printing mechanism against operation. When, now, a coin is dropped into the coin-chute, its impact against the incurved extremity of the locking-lever 65 swings such extremity out from the chute into the position shown in Fig. 1, and thereby releases the pin 63 from the notch 66. The small spring 64 then instantly withdraws the bell-crank lever from the dog 57, which swings away from the disk 56, and hence leaves the impression member free to be operated. To limit the impressions to a certain specified number, I journal on the impression member 50 a ratchet-wheel 70, formed with as many teeth as the designated number of prints to be made for one coin. Rigid with the frame-head 9 is a depending plate 73, carrying a pawl 72, swinging between stops 75 and elastically pressed toward the ratchet-wheel 70 by a leaf-spring 74. Fixed to the face of this wheel is a cam 71, which at the end of a complete revolution of said wheel will meet the arm 62, which is fixed on the shaft 61, and thereby raise said arm, and so cause the bell-crank lever 60 to swing over to present the pin 63 to the notch 66 and push the dog 57 into engagement with the disk 56. This will of course immediately terminate further motion of the printing mechanism until another coin has been inserted. This intermittent rotation of said wheel 70 is caused by the contact of its teeth with the pawl 72 as the impression member 50 rises to its topmost position, ten movements of the said member producing an entire revolution of a ten-toothed wheel.

The cardboard of suitable thinness or other paper to be printed upon is provided in a long strip and fed by means of feed-rolls 81, arranged to operate as the impression member is rising. This paper 80 is of a width to equal the length of the cards to be printed, it being cut in sections of suitable width at the end of the upward movement of the impression member, so that the action of the feed-rolls first throws forward the section of paper just printed and then the shears sever the same from the rest of the paper and deliver it to the delivery-shelf 3. The operation of the feed-rolls 81 is accomplished by the rack 83, rigidly supported by the side frame 5 and meshing with the pinion 82, and the pawl and ratchet 85 84 serving to convert the reverse turnings of the pinion 82 into an intermittent rotation forward. The shears comprise the blade 90, coacting with a companion blade 91 and yieldingly held out of contact with the latter by the leaf-springs 92, both blades being carried by the impression member. Just before said member reaches the upper extremity of its stroke the

blade 90 meets the fixed abutments or stops 92, held by the posts 8, and so produces the shearing action which severs the paper and permits the printed card to slide down to the delivery-shelf 3.

5 Inasmuch as the racks 16 are each very narrow and close together and it is necessary to locate the finger-pieces 19 far enough apart to be readily taken hold of and moved without interference with each other I shape the shanks 18 as indicated more clearly in Fig. 3—that is, I provide each rack with a vertical descending arm 17, having a lateral elbow at its lower end, to which is fastened the forwardly-reaching shank 18. By increasing the lengths of such arms for the central racks and increasing the lengths of the elbows for the outer racks the desired greater distance between the shanks, and hence between the 15 finger-pieces, is easily obtained.

10 As shown in Fig. 4, the machine-case is provided with a shelf or plate 100, which is formed with parallel slots 101, up through which project the finger-pieces 19 and along 15 which the latter are movable. At the sides of more or less of those slots are inscribed alphabetic characters 102, so arranged in relation to the finger-pieces that when any one of the latter is brought out into alignment 20 with any particular letter the type-disk connected with such finger-piece will present the same letter to the proper point for printing.

25 What I claim as my invention, and for which I desire Letters Patent, is as follows, to wit:

30 1. A printing-machine composed of a plurality of type-carrying devices, each containing substantially an entire alphabet, an impression member coöperating with the same, inking devices, means for presenting material to be printed on thereby and for delivering the same in separate slips each containing one impression of the matter set up on said type-carrying devices, and a lock automatically terminating further operations of the 35 machine upon the printing and delivery of a predetermined plural number of said slips.

40 2. A printing-machine comprising devices for setting up a line of type, an impression member coöperating therewith, inking devices, means for presenting a length of paper and cutting the same into duplicate lengths corresponding in number to the printing operations of the machine, and a lock automatically 45 acting to terminate further printing after a predetermined plural number of impressions.

40 3. A printing-machine comprising devices for setting up a line of type, an impression member coöperating therewith, inking devices, paper feeding, cutting and delivery mechanism, and a lock automatically acting to terminate further operation after a predetermined plural number of prints have been 55 made and delivered.

4. A printing-machine comprising type-selecting devices, a reciprocating impression member, type-inking devices operated by the movement of said member toward the type, paper-feeding mechanism operated by the opposite motion of said member, a paper-cutter operated by the latter part of this last-named motion, and a locking device for said member automatically acting after a predetermined plural number of movements of 70 said impression member.

5. The combination with a reciprocating impression member and a lock therefor, of a toothed wheel carried by said member, an arm rigid with said wheel and constructed to engage said lock at a designated point in said wheel's rotation and put the same into control of said impression member, and a fixed pawl constructed to be met by the teeth of 75 said wheel and to thereby intermittently rotate the latter.

6. The combination with a reciprocating member and a shaft for its actuation, of a ratchet-disk fixed on said shaft, a pawl engaging said disk, a second disk fixed on said shaft 90 and having one or more notches in its periphery, a dog normally out of engagement with said notched disk, a lever constructed to hold said dog in engagement with said notched disk, a lock for said lever, and means operated by a predetermined number of movements of said reciprocating member for forcing said lever into the control of said lock and for moving said dog into engagement with 95 said notched disk.

100 7. The combination with a cylindrical printing-surface and an impression member coöperating therewith, of a swinging frame mounted slightly eccentric to said cylindrical printing-surface, an inking-roll loosely carried by said frame normally out of contact with the printing-surface, and means operating said frame by the reciprocation of said impression member to carry said inking-roll into contact with the printing-line of said surface and then beyond and out of the way of the impression member when the latter meets the printing-surface.

115 8. The combination with a printing-surface and a frame provided with a plurality of vertical rods, an impression member slideable on said rods, a shaft having means for its rotation and revolvably supported by said frame, a ratchet-wheel fixed on said shaft, a fixed pawl engaging with said ratchet-wheel to prevent a backward turn to said shaft, a crank-arm fixed on said shaft, and a pitman between said crank-arm and impression member.

120 9. In a printing-machine, the combination of a series of type-disks mounted side by side, 125 a closed case for said parts, external keys for individually setting said disks, a rod movable in supports parallel with the axis of said disks, and external means for its operation; said disks having each a row of openings concen- 130

tric with its center and corresponding in number and arrangement with the type on its periphery; whereby, as each disk is set to present a determined character, said rod is advanced to enter one of the holes therein and thereby locks it against displacement.

10. In a printing-machine, the combination of a series of type-disks mounted side by side, a closed case for said parts, external means for individually setting said disks, a rod longitudinally movable in supports parallel with the axis of said disks, an external pointer connected with said rod for its operation, and a dial provided with characters designating each of said disks; each of said disks having a row of openings concentric with its axis and corresponding in number and arrangement with the type on its periphery; whereby, as each disk is set to present a determined character on its periphery, said pointer is turned to the proper character on said dial to cause said rod to enter an opening in such disk and thereby lock it in position.

25 11. In a printing-machine, the combination of a series of type-disks mounted on a common axis, each having a row of openings concentric with such axis and corresponding

in number and position to the type on its periphery, a slotted tubular support parallel with the axis of said disks and in alinement with said openings, a rod slideable in said tube and having a pin projecting through said slot, a swinging arm engaging said pin, a segmental gear rigid with said arm, a pinion meshing with said segmental gear, and a pointer connected with said pinion.

12. In a printing-machine, the combination of a series of comparatively thin type-disks mounted side by side on a common axis, each disk having type upon a portion of its periphery and gear-teeth upon the remainder thereof, a rack for each disk, a shelf having parallel slots through it at substantial distances apart, keys rising through said slots and rigid connections between said keys and racks; said connections being offset as described to avoid mutual interference.

In testimony that I claim the foregoing invention I have hereunto set my hand this 17th day of June, 1904.

GEORGE ALBERT MOORE.
